UNITED STATES PATENT OFFICE.

GERALD DEAKIN, OF ANTWERP, BELGIUM, ASSIGNOR TO WESTERN ELECTRIC COMPANY, INCORPORATED, OF NEW YORK, N. Y., A CORPORATION OF NEW YORK.

TELEPHONE HAND SET.

Application filed September 7, 1922. Serial No. 586,618.

To all whom it may concern:

Be it known that I, GERALD DEAKIN, a citizen of the United States of America, residing at Antwerp, Belgium, have invented 5 certain new and useful Improvements in Telephone Hand Sets, of which the following is a full, clear, concise, and exact description.

This invention (on which an application, 10 No. 182,956, was filed in Great Britain on April 20, 1921,) relates to telephone hand sets.

An object of the invention is to provide 15 a hand set to which an impulse sender may be easily attached and from which it may be readily removed.

For testing purposes in exchanges employing 20 automatic switching apparatus it is necessary that a hand set be equipped, in addition to the usual transmitter and receiver, with a device capable of transmitting switch-operating electrical impulses, when desired, to the switches under test. Such impulse transmitting devices usually consist of a 25 finger-hole calling dial, the operation of which controls the opening and closing of a pair of contacts located in the line circuit leading to the switch under test.

It is desirable in such a hand set that the 30 calling dial be adapted to be readily attached to and detached from the instrument, and, when attached, to be electrically connected with the operating circuits of the transmitter and receiver. The hand set, 35 however, should be designed so that when the dial is detached the usual series circuit including the transmitter and receiver may be automatically closed. Thus, the set may be used for testing purposes in connection 40 with either an automatic or a manual exchange, and in the latter case need not be encumbered with the calling dial. This arrangement also possesses the advantage that when a telephone linesman is carrying a 45 test set he may fasten the hand set to his belt while he carries the calling dial in his pocket or in some other protected place.

The present invention provides such a hand set, certain embodiments of which are 50 shown in the accompanying drawings.

Fig. 1 is a rear elevation of the hand set showing the calling dial in position.

Fig. 2 is a side elevation of the hand set with the calling dial attached in which part 55 of the casing is broken away so as to show

a portion thereof as a section upon the line 2—2 in Fig. 1.

Fig. 3 shows diagrammatically the electrical circuits of the set with the dial switch in position.

Fig. 4 is a detail view showing the method of attaching the dial switch to the hand set.

Fig. 5 is a sectional view upon the line 5—5 of Fig. 4.

The stem 1 of the hand set is a U-shaped 65 section closed by a front plate 2, which is held in position by means of screws 3, screwing into columns 4, attached to the rear side of the stem. The stem 1 carries the usual receiver 5 and transmitter 6. Attached to 70 the front plate 2 by means of rivets 7, is a stiff spring 8, the lower end 9 of which is rounded as shown, and projects through a slot 10 cut in the plate 2. On each side of the spring 8 is mounted a pair of downwardly extending flat leaf springs 11 and 12, insulated from each other and from the stem, and secured to the front plate 2 by means of screws 13. The springs 12 extend 75 downwardly further than the spring 11. To 80 each spring is secured a lug 14 to which the electrical connections are taken as will be explained later.

The calling dial 15 used is of the well-known construction and need not be described in detail. It is secured to bosses 16 attached to or formed integrally with the inside back plate of a round hollow casing 17, the mouth of which is open to permit the operation of the finger plate. Secured to 90 the back of the casing 17 is a pair of round studs 18 which are held in position by nuts 19 screwing on to a threaded portion of smaller diameter passing through the casing. The studs 18 are hollow; and passing there- 95 through, but insulated therefrom by insulating bushings 20, are pins 21, which are held in position by nuts 22. On opposite sides of each stud 18 on the outside of the casing are cut shoulders 23 so that when the 100 studs are fixed in position there exist between the back of the casing 17 and the shoulders 23 of the studs 18 slots of a width equal to the thickness of the material of which the front plate 2 is formed. A slot 105 24 of the same size as the slot 10 in the front plate 2, is cut in the casing 17.

The front plate 2 has cut therein a pair of slots 25, which extend parallel to the length of the plate and are spaced apart a 110

distance equal to the distance between the studs 18. The width of the slots is equal to the width of the smaller cross section of the studs 18 at the shoulders 23. The upper ends 26 of the slots 25 are enlarged and surrounded as shown so as to permit the passage of the studs 18 therethrough. The springs 12 attached to the front plate are of such a length and are so located as to extend below and opposite to the slots 25. A hole 27 is provided in the lower portion of the front plate 2 through which passes the cord 28 containing the usual conductors for connecting up electrically the elements of the instrument.

In Fig. 3 the electrical connections of the instrument are diagrammatically illustrated. The receiver 5 and transmitter 6 are connected in series through the springs 11 and 12, which are normally closed when the calling dial is not attached. The dial is connected to the pins 21, while the leads 29 and 30 may terminate in suitable clips for making electrical connection with a desired line.

To attach the calling dial to the instrument, the studs 18 are pushed through the rounded ends 26 of the slots 25 and the casing 17 containing the dial is then pushed down until the ends of the slots 25 are engaged by the studs 18 when the rounded end 9 of the spring 8 passes through the slot 24 in the casing 17. The shoulders 23 upon the studs 18 engage the front plate 2 so that this plate fits between the shoulders and the casing 17 as clearly shown in Fig. 5. The pins 21 engage the springs 12 and push the latter out of engagement with the springs 11 so that the calling dial is now connected in series with the receiver and transmitter.

The invention claimed is:

1. A telephone hand set, a calling dial detachably secured thereto, an electric circuit in the hand set, means for inserting the dial in said circuit when the former is attached to the hand set and for cutting the dial out of the circuit and automatically closing the circuit when the dial is detached from the hand set.

2. In a telephone instrument, a receiver, a transmitter, an operating circuit therefor, a connecting stem, a calling dial detachably mounted on the stem, and means for keep-

ing said circuit closed at all times and for keeping it closed through the dial when, and only when, the latter is attached to the stem. 55

3. In combination, a telephone hand set comprising a stem, slots therein, a calling dial, studs in the dial to engage said slots and to hold the dial upon the hand set, said studs forming the electric terminals of the 60 dial, and contacts in proximity to the studs for engaging the studs.

4. In combination, a telephone hand set comprising a stem member, a calling dial, a case for the dial, an opening therein, a pair 65 of slots in said stem, a pair of studs on said case having shoulders thereon to engage said slots and to hold the dial upon the hand set, said studs forming the electric terminals of the dial, a pair of contacts in proximity 70 to the slots for engagement to studs, and a spring member fixed to the stem of the hand set and passing through an opening therein to engage the opening in said case when the dial is attached to the stem so as to lock the 75 dial in place.

5. In combination, a telephone hand set comprising a stem, an electric circuit therein, a calling dial, a casing therefor, a pair of slots in said stem, a pair of studs on the 80 dial casing to engage said slots and to hold the dial upon the hand set, the studs forming the electric terminals for the dial, a pair of contact springs adapted normally to close the electric circuit and upon operation of 85 said studs to insert the dial in said circuit when it is attached to the hand set.

6. In combination, a telephone hand set comprising a stem, an electric circuit therein, a calling dial, a pair of slots in said stem, a pair of studs on the dial to engage said slots and to hold the dial upon the stem, a pair of contact pins passing through said studs, a pair of contact springs in the hand set to engage the pins and to electrically 95 connect the dial and the hand set when the dial is in engagement therewith, and to automatically close said circuit when the dial is not in engagement therewith.

In witness whereof, I hereunto subscribe my name this 18th day of August, A. D. 1922.

GERALD DEAKIN.
